UNITED STATES PATENT OFFICE.

OSCAR F. FORSBERG, OF NEW YORK, N. Y., ASSIGNOR TO WESTERN ELECTRIC COMPANY,
OF NEW YORK, N. Y., A CORPORATION OF ILLINOIS.

ELECTROMAGNETIC DEVICE.

1,163,903.

Specification of Letters Patent.

Patented Dec. 14, 1915.

Application filed September 29, 1909. Serial No. 520,162.

To all whom it may concern:

Be it known that I, OSCAR F. FORSBERG, citizen of the United States, residing at New York, in the county of New York and State of New York, have invented a certain new and useful Improvement in Electromagnetic Devices, of which the following is in full, clear, concise, and exact description.

My invention relates to electromagnetic devices and is particularly useful in connection with telephone apparatus known as "combined jacks and signals."

One feature of the invention relates to the provision of a new and improved magnet and armature structure, which is highly efficient as to its electrical characteristics and which permits the ready removal of the magnet coil for purposes of repair.

Another feature of the invention consists in providing, as an integral part of the magnet shell, wings upon which jack and contact springs may be mounted.

My invention will be more readily understood by reference to the accompanying drawings, in which

Figure 1 is a perspective view of a combined jack and signal embodying my invention and showing the target in its operated position; Fig. 2 is a side elevation, partly in section, showing the parts in their normal positions; Fig. 3 is a partial sectional view showing, more particularly, the contact structure whereby the electromagnet is connected in circuit, and also the night alarm mechanism, the parts being in their normal positions; Fig. 4 is a partial plan view, partly in section, showing the parts in their normal positions; Fig. 5 is a sectional view on the line 5—5 of Fig. 4; Fig. 6 is a partial side elevation, partly in section, showing the plug in position in the jack and its action in restoring the target; Fig. 7 is a partial side elevation, partly in section, showing the target in its operated position and its action upon the night alarm contact springs; Fig. 8 is a partial horizontal sectional view showing the electromagnet partially removed from the shell, the manner of securing it in position, and the contact structure associated therewith; Fig. 9 is a vertical longitudinal sectional view of the target on line 9—9 of Fig. 10; Fig. 10 is a vertical transverse sectional view of the target on the line 10—10 of Fig. 9; Fig. 11

is a perspective view of the target; Fig. 12 is a plan view of a sheet metal blank from which the magnet shell may be formed; and Fig. 13 is a front elevation of the armature and arm carried thereby.

Like characters of reference are used to designate like parts throughout the several figures.

Referring to the drawings, a mounting is provided comprising a plate 14 to which a U-shaped frame 15 is secured in some suitable manner, as by means of screws 16 passing through the plate and engaging the ears 18. Secured to the rear wall of the frame 15 is a shell 19, preferably formed from a sheet metal blank. A blank of suitable form is shown in Fig. 12, wherein 19 is the body portion, 20 and 21 are wings or extensions, and 22, 23, 24 and 25 are lugs. When a blank of the form shown is properly formed into a shell, the body portion 19 serves as the shell proper, the wings or extensions serve as a mounting for the jack springs, and the lugs 22, 23, 24 and 25 provide means for readily securing the shell to the rear wall of the frame 15, said lugs being adapted to pass through suitable apertures in said wall and be secured thereto by swaging in a manner well understood.

Within the shell 19, as shown in Fig. 8, is an electromagnet 26, said electromagnet being removably secured in position by means of a screw 27 passing longitudinally through the core 28 and engaging with some fixed part, as, for example, the rear wall of the frame 15. The free end of the core of the electromagnet carries a circular pole piece 29, which may readily be made of a series of punched circular disks 30, 31 and 32. Mounted preferably upon the front face of the rear wall of frame 15, as shown in Figs. 3, 4 and 5, is a group of springs comprising two U-shaped contact springs 33 and 34, the free ends of said springs lying adjacent apertures 35 and 36, through which terminals 37 and 38 carried by the electromagnet may pass and make contact with said U-shaped springs. An armature 39 having an opening whereby it may loosely embrace the pole piece, is pivotally carried upon the rear end of the shell 19 the surface of which is entirely in one plane. Insulatively mounted upon the wings or extensions 20 and 21 of the shell 19 are three

jack springs comprising two line springs 40 and 41 and a cut-off spring 42, said line springs preferably being disposed on opposite sides of the extensions, and the entire group being secured thereto by means of screws 43 and 44 passing through apertures 45 and 46 in said extensions. The jack spring 40 and the cut-off spring 42 may be permanently connected with the U-shaped contact springs 33 and 34, respectively, by means of suitable conductors, as, for example, the wires 47 and 48.

With the construction thus described, the electromagnet 26, when secured in position 15 in the shell 19 by means of screw 27, is in electrical connection with the jack springs through the contact of its terminals 37 and 38 with the U-shaped springs 33 and 34, and pole piece 29 is in operative relation to the armature 39. By merely unscrewing the screw 27, the electromagnet 26 may be withdrawn through the armature 39 without opening any soldered or other permanent electrical connections and without disturbing 25 any associated parts.

Within the frame 15 is a centrally pivoted target 49, preferably of approximately spherical form, said target being so mounted as to protrude through a circular aperture in the plate 14 and rock freely therein. Referring particularly to Figs. 9, 10 and 11, the target may comprise segmental elements 50, 51 and 52 embraced by two drawn cups 53 and 54 carried upon a shaft 55, the assembled structure being enameled or otherwise provided with a white portion 74 and a black portion 75. The segmental element 50 is provided with a catch 56 and the segmental element 52 is provided with a forwardly extending projection 57. The catch 56 is adapted to normally engage with lateral projection 58 of the arm 59 carried by the armature 39, and the forwardly extending projection 57 is adapted to engage a lateral projection 60 carried by said arm when the target is restored, as more fully hereinafter described. The segmental element 51 is merely a distance piece adapted to suitably separate the adjacent elements 50 and 52. Cup 53 is provided with an integrally formed projection 61, adapted to be engaged by the lever 68 when the target is restored, and cup 54 is provided with an integrally formed projection 63 adapted to control the night alarm springs 64 and 65 when the target is released. The night alarm springs, which preferably are L-shaped, may conveniently be insulatively comprised with the two U-shaped terminal contact springs 33 and 34 in a group secured to some suitable fixed part adjacent the end of the electromagnet, as, for example, the rear wall of the frame 15, by means of screws 66 and 67.

Referring to Figs. 1, 2, 3, 4, 6 and 7, a bell crank lever 68 is pivotally mounted

within the frame 15, said lever having two arms 69 and 71. Arm 69 extends downwardly between jack springs 40 and 41, and into the path of the plug, said arm being provided with insulation 70 at its lower end 70 to prevent electrical contact therewith of the plug. Arm 71 extends forwardly and is adapted, when the lever is tilted or rocked by the plug, to engage projection 61 of the target as hereinafter more fully described. 75

Referring particularly to Fig. 6, 72 is a jack thimble and 73 is an ordinary switch-board plug.

The mode of connecting the combined jack and signal with the telephone line circuit will be readily understood without description. 80

Referring to Figs. 2, 3 and 4 showing the parts in their normal positions, with the black portion 75 of the target exposed, the energization of the electromagnet, as by ringing current from a generator at the subscriber's station, causes the armature 39 to be attracted and the arm 59 to be lifted, thereby disengaging the lateral projection 90 58 from the catch 56 and allowing gravity to tilt the target in a counter-clockwise direction, as viewed, for example, in Fig. 2, and bring it to its operated position with the white part 74 exposed, as shown in Figs. 1 95 and 7. In said operated position, the projection 61 of the target is adjacent the end of the arm 71 of the bell crank lever 68, as shown in Fig. 1, and the projection 63 of the target is resting upon the night alarm 100 spring 64, thereby forcing it into contact with its companion spring 65, as shown in Fig. 7. When the operator inserts the plug 73 into the jack in response to the signal, the tip of the plug strikes the arm 69 of the bell crank lever 68, thereby tilting said lever and, through the medium of the arm 71 and projection 61, forcing said target to its normal position, in which position said target is retained by the engagement of the catch 110 56 with the lateral projection 58 of the arm 59 carried by the armature 39. In case, however, the calling current leaves the core of the electromagnet sufficiently magnetized to hold the armature, as sometimes occurs when 115 said core is not of proper composition or not properly annealed, the arm 59 will not be held in its operated position since the restoration of the target will bring the forwardly extending projection 57 into engagement with the lateral projection 60 of the arm 59 carried by the armature 39, thereby forcing said armature to its normal position. It will readily be understood that without the provision of this feature, the armature, 120 if retained, as described, by residual magnetism, would hold the arm 59 in its elevated position and prevent the engagement of the catch 56 and lateral projection 58, whereby the target would again fall to its 125 130

operated position when the plug was withdrawn after conversation, thereby giving a false signal.

Although my invention is illustrated by 5 embodiment in a signal wherein the armature is in the form of a ring, it will be readily understood that other forms might be used without exceeding its scope, as, for example, a forked armature or other form 10 adapted to allow the electromagnet to be removed without disturbing adjacent parts. Also it is obvious that the feature of my invention which provides for the removal of the electromagnet is not limited, in its application, to combined jacks and signals, nor to electromagnets inclosed in shells, but 15 may readily be embodied in drops, relays or any device employing an electromagnet wherein the return pole piece or other structure would interfere with the removal of the electromagnet laterally. These and similar modifications I regard as clearly within the scope of my invention.

Having described my invention, I claim:

25 1. In a combined jack and signal, a magnet coil, a core therefor, a magnetic shell surrounding said coil, the surface of one

end of said shell being entirely in one plane, a circular pole piece, and a pivoted armature having a circular opening loosely fitting the exterior of said pole piece and co-operating with said end of the magnetic shell. 30

2. In a combined jack and signal, a magnet coil, a core therefor, a magnetic shell surrounding said coil, the surface of one end 35 of said shell being entirely in one plane, a circular pole piece carried by said core and located beyond the end of said shell, and a ring armature pivoted at the end of said shell and having its circular opening loosely fitting the exterior of said circular pole piece. 40

3. In a combined jack and signal, a magnet coil, a sheet metal shell surrounding said coil and having downwardly projecting 45 wings, and jack and contact springs carried by said wings.

In witness whereof, I, hereunto subscribe my name this 27th day of September A. D. 1909.

OSCAR F. FORSBERG.
